UNITED STATES PATENT OFFICE

2,604,638

MOBILE BATHING AND LIFT APPARATUS

Lewis P. Furry, Santa Rosa, Calif.

Application March 5, 1947, Serial No. 732,563

3 Claims. (Cl. 4—185)

1

My present invention relates to an improved Mobile Bathing and Lift Apparatus and more especially to a mobile tub for use particularly in hospitals where bathing of ill or injured persons is desirable and providing stretcher means upon which the person may be placed directly from the bed and lowered into the tub.

The invention includes mechanical means for lowering or elevating the stretcher or support into and out of the bath water and for lateral movement of the support with relation to the frame so that the stretcher may be extended over the bed and under the patient.

By this means the patient may be bathed with a minimum of movement and the apparatus may be moved easily from place to place in the establishment.

In the accompanying drawings I have illustrated one complete example of the physical embodiment of my invention according to the best mode I have thus far devised, but it will be understood that various changes and alterations may be made in the exemplified structure within the scope of the appended claims.

In the drawings:

Fig. 1 is a side elevational view of the apparatus of my invention.

Fig. 2 is a top plan view thereof.

Fig. 3 is an end elevational view of the apparatus.

Fig. 4 is a transverse vertical sectional view at line 4—4 of Fig. 1.

Fig. 5 is a sectional view showing the stretcher or support in extended position.

Fig. 6 is a longitudinal vertical sectional view taken on line 6—6 of Figure 2.

Fig. 7 is a sectional plan view of the structure taken on line 7—7 of Figure 1 showing the hinged end portions by means of which in alternate use the patient's head may be supported above the water line.

Figure 8 is a cross section through the upper part of the frame taken on line 8—8 of Figure 2, with parts omitted.

Referring now to the drawings wherein I have illustrated the present preferred embodiment of my invention, I employ a tub 2 supported upon the base 4 having caster wheels 6, and a drain spigot 8 is provided for the tub.

At the corners of the rectangular tub I mount angle bars 10 suitably secured and on the upper ends of these bars I provide a platform 12 longitudinally supported by bars 14.

In the parallel pairs of vertical, spaced plates 16 and 18 are journaled a pair of shafts 20 and

2

22. The shaft 20 is driven by a sprocket 24 fixed to one end thereof by chain 26 having drive connection with a sprocket 28. A crank 30 fixed to the pinion 28 will by manual operation thereof cause rotation of the pinion 28 and subsequent rotation of the gear 24 and shaft 20 through the medium of the chain 26.

On the shaft 22 between the pairs of plates 16—18 I affix sheaves 34 and each sheave carries cables 36 and 38 thereon to secure the close corners of the vertically movable lift 40. This lift has side rails 42 and the end portions 44 of the lift are hinged at 46 to permit elevation thereof and they may be secured in adjusted position by bails 48 engageable in the serrations 50 of the side rails.

The shaft 22 is manually rotated by a hand crank 21, pivotally mounted on the plate 16 at one end of the frame. The crank rotates a sprocket 23 over which a chain 25 is trained and the chain rotates a sprocket 27 on the end of the shaft 22.

By the use of this mechanism, the apparatus may be moved to the side of a bed, and the lift 25 adjusted to the same height by operation of the shaft 22. The patient may then be moved onto the lift, and the lift is lowered so that the patient is immersed in the water.

In addition it is often necessary to raise a patient from the floor as from a stretcher without moving the limbs of the patient.

For such needs I provide the carrier 52 supported by cables 54 passing through the sliding support 56 having pulleys 58. These cables are attached to the pulleys or sheaves 60 on the shaft 20 and the sliding support is secured between guides 62 permitting lateral movement of the sliding support. Movement of the shaft 20 in one direction as seen in Fig. 4 will first extend the sliding support laterally and will then upon movement in the opposite direction permit the lowering of the carrier 52.

The patient may be lifted from the floor by elevation thereof, subject to rotation of the shaft 20, and when the carrier reaches a point level with the lift 40 the patient may then be moved from the carrier to the lift and the lift with the patient thereon may then be lowered into the bath water.

By the utilization of the apparatus of my invention all unnecessary handling of the patient will be avoided and the injured person may be moved either from a bed, or from the floor by the mechanical appliances incorporated in the bathing apparatus.

Having thus fully described my invention what I claim as new and desire to secure by Letters Patent is:

1. In a bath apparatus having a mobile tub provided at its four corners with vertical uprights and a platform at the top of the uprights having a shaft journalled thereon adapted to operatively raise and lower a lift in said tub by means of cable connections between said tub and said lift the improvement comprising guide means carried by said platform at each end thereof, a support slidably mounted in said guide means, a second shaft journalled on said platform in parallel relation to said first shaft, and cable means connected to said second shaft and passing through the four corners of said support, a carrier connected to said cables and means for operating said second shaft whereby said cable will raise and lower said carrier in relation to said support.

2. In a bath apparatus, a tub, vertical uprights in the corners of the tub, a platform on the

upper ends of the uprights, a pair of shafts journalled above the platform, a support slidably mounted on said platform and cable means operatively connecting one shaft to a lift within the tub and a carrier carried by said support exteriorly of the tub whereby a patient may be raised from the floor by the carrier and moved to the lift to be lowered into the tub.

3. The invention as in claim 2 wherein guide means is provided for said support so that said support can be moved outwardly of the platform.

LEWIS P. FURRY.
